UNITED STATES PATENT OFFICE.

SAMUEL ERB, OF TACOMA, WASHINGTON.

LOG-CARRIAGE-OFFSETTING MECHANISM.

Application filed May 28, 1921. Serial No. 473,546.

To all whom it may concern:

Be it known that I, SAMUEL ERB, a citizen of the United States, and a resident of the city of Tacoma, county of Pierce, State 5 of Washington, have invented certain new and useful Improvements in Log-Carriage-Offsetting Mechanism, of which the following is a specification.

My invention relates to improvements in 10 log carriage offsetting mechanism, and more particularly to mechanism of that character used in connection with the carriages whereon logs are mounted for movement against the ripping saws. The principal object of 15 the present invention is to provide mechanism that operates automatically to move the carriage laterally at the start of each forward and reverse movement so that the log thereon will be moved clear of the saw 20 while it is being moved back to position for the following cut.

Another object of the invention is to provide a device of the above character that embodies a minimum number of parts and 25 which operates easily, and successfully performs its function.

Other objects of the invention reside in the details of construction and in the combination of parts whereby an efficient and 30 serviceable device is provided.

In accomplishing these and other objects of the invention, I have provided the improved details of construction, the preferred forms of which are illustrated in the accompanying drawings, wherein—

Fig. 1 is a plan view of a log carriage equipped with offsetting mechanism according to the present invention.

Fig. 2 is a longitudinal, sectional elevation of the carriage and its track, and showing the means whereby the offsetting mechanism is operated.

Fig. 3 is an enlarged plan view of one of the offsetting devices, showing in full lines its position while the carriage is moving to the saw, and in dotted lines showing its position while being returned.

Fig. 4 is a transverse sectional view through the carriage, showing the offsetting mechanism in front elevation.

Fig. 5 is an elevation of the locking lever used to prevent operation of the offsetting mechanism.

Referring more in detail to the drawings—

1 and 2 designate the opposite, longitudi-

nally extending side beams of a carriage whereon logs may be mounted for advancement to the ripping saw. This carriage is supported at its ends upon transverse axles 3 which are equipped at their opposite ends with wheels 4 and 4' adapted to travel upon the parallel rails 5 and 5' of a guide track; the wheels 4 at one side of the track are grooved and the rail 5 is made to fit the grooves of the wheels to prevent the latter from leaving the track as the carriage is moved forwardly and rearwardly. The undersides of the beams 1 and 2 are provided with guide grooves 6 or with bearings 70 wherein the axles 3 are disposed in such manner that the carriage may be moved thereon laterally with respect to the direction of the track.

In Figures 1 and 2 the saw for cutting 75 the logs advanced by the carriage is indicated at 8, and it is disposed adjacent the rail 5' in a plane parallel to the vertical plane of the rail.

Securely fixed to the axles 3, near the 80 beam 1, are collars 9, each having an annular groove 10 about its center portion, and in these grooves, ring members 11 are mounted so that they will turn freely within the grooves. Preferably the ring members will be made up of two semi-circular parts, joined together at their ends by means of bolts 12, also, the collars will be made in two parts that will fit opposite sides of the axles and will be clamped in position 90 against the axles by means of bolts 13 extended through the parts.

The rings 11 are provided on their upper and lower sides with projecting studs 14, and pivotally connected to these studs 95 are the outer ends of stop toggle connections, each of which consists of members 15 and 16 which are joined pivotally together at about the center of the toggles by means of vertical pivot pins 17. The 100 members 15 and 16 have substantial, engageable stops 18 thereon which engage each other when the members of the toggle are moved to extend in a straight line, as shown in Fig. 3, to stop further movement in that 105 direction. The extreme ends of each of the members 16 of the toggles are pivotally connected by means of pins or bolts 19 to brackets 20 that are fixed to the side beam 2 of the carriage.

It is apparent that with the toggles so connected to the log carriage and to the

axles 3 thereof, movement of the toggles to a position as shown in dotted lines in Fig. 3, will shorten the distance between the pivot points 14 and 19 and, since the wheels 4 are 5 grooved to hold to the rail, the carriage will be compelled to travel laterally on the axles a distance which will effectively clear the log thereon from the saw, and conversely, as the direction of travel of the carriage effects the straightening of the toggles, the carriage will be moved again to its normal position for advancement to the cut.

The means whereby movement is imparted to the toggles to effect the shifting of 15 the log carriages is best illustrated in Figures 1 and 3. In these figures, 25 designates a link that is pivotally connected at its inner end to the lower end of the bolt 19 beneath the bracket 20 and also is fixed to the lower 20 end of the bolt 17. At its outer end the link 25 is suitably connected with an endless cable 26 that passes about a pair of sheave wheels 27 and 28 located beyond the extreme limits of travel of the log carriage 25 and alined in the direction of its movement. One of these wheels is mounted upon a tightening frame, indicated at 29, so that the cable may be tightened, and on the axle of the other wheel is keyed a brake drum 30 about which a brake band 31 is mounted and which enables the required resistance to be placed upon the drum. This connection provides that when the carriage is reversed for its return movement, the friction of the 35 brake opposes sufficient pull on the cable to draw the link 25 to the position in which it is shown in dotted lines in Figure 3, forcing the toggles with it, to move the carriage to such position that the log thereon will be 40 cleared from the saw. Similarly, when the direction of movement of the carriage is reversed to carry the log to the saw, the friction of the brake on the drum will, by means of the endless cable give sufficient resistance 45 to pull the toggles to the straight position against their stops.

In order that the links 25 may be locked 50 against movement so that, if it becomes necessary to back a log away from the saw without offsetting, this may be done, I have provided locking levers of the character shown in Figure 5. These locking levers 55 are pivotally fixed by means of bolts 36 to the outside of the beam 1 closely adjacent the ends of the links 25, and each has a short lower end portion 37 which is adapted, when the lever is swung to one position, to

engage the end of the toggle control lever to hold it against movement and thereby prevent offsetting of the carriage, but when 60 moved to another position, will not interfere with movement of the toggle.

It is apparent that devices of the character disclosed are simple in construction and in operation and two or more may be 65 used on each carriage accordingly as is required.

Having thus described my invention, what I claim as new therein and desire to secure by Letters Patent is:

1. The combination with a pair of wheeled axles movable in reverse directions along guide rails, a carriage mounted for lateral shifting on the axles, a cable extended about wheels alined parallel with the rails and friction means for retarding movement of the cable, of stop toggle mechanisms connected with said axles, each comprising inner and outer members and a hinge pin connecting said members, the inner toggle members having pivot pin connections with the carriage frame and the outer members having pivotal connection with the axles, and actuating links for the toggles having their inner ends mounted on the connecting pivot pins of the toggle members and outer ends connected with the cable and adapted to open and close the toggles by connection with the hinge pins thereof.

2. The combination with a pair of wheeled axles movable in reverse directions along guide rails, a carriage mounted for lateral shifting on the axles, a cable extended about wheels alined parallel with the rails and friction means for retarding movement of the cable, of stop toggle mechanisms connected with said axles, each comprising inner and outer members and a hinge pin connecting said members, the inner toggle members having pivot pin connections with the carriage frame and the outer members having pivotal connection with the axles, and actuating links for the toggles having their inner ends mounted on the connecting pivot pins of the toggle members and outer ends connected with the cable and adapted to open and close the toggles by connection with the hinge pins thereof, and locking levers pivotally mounted on the carriage and movable to engage with the toggle actuating links to prevent their movement.

Signed at Seattle, Washington, this 23rd day of May, 1921.

SAMUEL ERB.
